THERMOSTATIC SWITCH

William A. Yonkers, Mountain Lakes, N. J., assignor to Radio Frequency Laboratories, Inc., Boonton, N. J., a corporation of New Jersey

Application March 5, 1948, Serial No. 13,239

3 Claims. (Cl. 200—137)

1

This invention relates to temperature actuated control devices and more particularly to a thermostatic switch of novel construction and operation.

Thermostatic switches as a class are well known and established in the art. In general such devices comprise a temperature sensitive element capable of producing a motional displacement related to changes in the surrounding air temperature. The motional displacement is employed to open or close a set of suitable contacts thereby opening or closing an electrical power or signal circuit.

The adaptation of thermostatic switches to the control of relative high current and/or voltage circuits presents design problems of a conflicting nature. A slow or gradual opening of this type of circuit produces a prolonged electrical arc which rapidly deteriorates the contact material. Such destructive action may be overcome by making the contacts sufficiently massive to dissipate the heat generated at the point of the electrical arc. However, massive contacts, in turn, increase the over-all size of the device and reduce the sensitivity and operating accuracy of the thermostat.

It has been proposed to solve the problem relating to heavy duty thermostatic switches by employing permanent magnets in conjunction with the actual circuit breaking contacts, or by employing various leverage and gear mechanisms, designed to cause a sudden opening of the contacts when the temperature reached the value for which the device is adjusted. While such devices are satisfactory for certain applications they cannot be held to a close operating tolerance, that is, the temperature at which the contacts close will in time vary substantially from the preset or adjusted value. Further, a relatively wide change in temperature is required between the contact closing and contact opening operation.

The above problems become aggravated when the thermostatic switch is to be designed for high temperature operation as such applications impose limitations with respect to the materials that may be employed, their size, form and action within the device itself.

An object of this invention is the provision of a thermostatic switch adapted for relatively high temperature use and provided with simple means for the snap actuation of contact elements whereby the switch may be used to control an electrical circuit of relatively high current and/or voltage.

2

An object of this invention is the provision of a thermostatic switch including cooperating members having different thermal expansion coefficients and means for translating the relative motion between the said members into an abrupt movement of a movable contact whereby the movable contact will close and open an electrical circuit at predetermined values of temperature.

An object of this invention is the provision of 10 a thermostatic control wherein a relatively small gradual motion of an expansible member is translated into a relatively large, abrupt motion of an electrical circuit control member.

An object of this invention is the provision of 15 a temperature actuated control comprising concentrically disposed members having different thermal expansion coefficients, a stressed disc, means for imparting a sudden, snap-action motion to the stressed disc at a predetermined increment of relative expansion between the concentrically disposed members, and contact members adapted to open and close an electrical circuit in response to motion of the stressed disc.

An object of this invention is the provision of 20 25 a temperature actuated control comprising a housing enclosing a pair of spaced terminal members, a movable member normally closing an electrical circuit through the terminal members, a conically stressed disc disposed within the housing, means for applying a force along the circumference of the disc and normal to the plane of the disc to produce an abrupt reversal in the curvature of the disc, and means effective to displace the movable member in accordance with the motion of the disc to thereby open the electrical circuit through the terminal members.

An object of this invention is the provision of 30 35 a high temperature thermostatic switch adapted to open a relatively high current electrical circuit at a preset temperature and which switch is of small size, light weight, and of simple construction and long operating life.

These and other objects and advantages will 40 45 be apparent from the following description when taken with the accompanying drawings which are for purposes of illustration only and are not to be construed as defining the scope or limits of the invention.

In the drawings wherein like characters refer 50 to like parts in the several views:

Figure 1 is an elevation view of a thermostatic switch made in accordance with this invention;

Figure 2 is an end view of the device;

Figure 3 is a central cross-sectional view taken 55 along the line A—A of Figure 2 and showing the

contact members in circuit closed position; and Figure 4 is a cross-sectional view similar to Figure 3 and showing the contact members in circuit open position.

Referring to Figures 1 and 2, a thermostatic switch made in accordance with this invention comprises a base 10, casing 11 and a tubular shell 12 substantially as shown. The casing 11 is provided with a set of apertured extensions 13 that serve as a means for mounting the device upon a piece of apparatus.

The construction and assembly details of the thermostatic switch are shown in the central cross-sectional views, Figures 3 and 4.

A subbase 14, made of suitable insulating material such as a silicone compound which is also suitable for high temperature operation, is provided with a pair of openings through which are inserted the contact terminals 15 made of metal. The terminals 15 are provided with integral heads 16 and are secured in position by the mounting nuts 17, as shown. Additional nuts 18 are provided for the purpose of fastening wires from an external circuit to the terminals 15.

The inner surface of the subbase 14 has an axial bore within which is disposed a cup-shaped movable contact 19 having an outer surface 20 of platinum, silver or other material having good electrical contacting properties. A similar surface 21 (see Figure 4) is provided on the heads 16 of the terminals 15 as by plating, welding, etc. The compression spring 22 provides a biasing force tending to establish a closure between the movable contact and the terminals. Thus, in the position illustrated in Figure 3, a good electrical circuit is made between the two terminals 15.

Abutting against the subbase 14 is a metal washer 23 having a central aperture therein, said washer 23 being spaced from the base 10 by a metallic cylinder 24. It will be apparent the subbase 14, washer 23 and cylinder 24 are firmly fixed in position when the edge 25 of the base 14 is turned over the shoulder of the subbase 14, substantially as shown.

A metal ring 26 having an inwardly extending radial shoulder 27 lies within the cylinder 24 and is biased against the base 10 by the force exerted by the spring washer 28 disposed between the ring 26 and the washer 23. A stressed, snap-action disc 29 is disposed within the ring 26 and rests against a circular ridge formed in the shoulder 27 of the said ring 26, substantially as shown. It should be noted the apex of the ridge forms a circle having a diameter less than the diameter of the disc 29, that is, the edge of the disc overhangs the ridge beyond the point of mutual contact. The disc 29 is preformed to have a normally concave curvature as shown in Figure 4, and carries an axial plunger 30 that is secured thereto by a screw 31. The plunger 30 is made of a material having good electrical insulation properties and capable of withstanding high temperatures such as, for example, a silicone molding compound. A cone-shaped member 32 has its apex aligned with an opening in the base 10 and its base contacts the disc 29 circumferentially beyond the point of contact between the disc and the ridge of the shoulder 27.

When the disc 29 has a normal concave curvature, as shown in Figure 4, the plunger 30 extends into the bore of the subbase 14 thereby preventing contact between the movable contact 19 and the terminals 21. However, when a sufficient pressure is applied to the apex of the member 32, the disc abruptly changes its curva-

ture from concave (Figure 4) to convex (Figure 3). The change in the curvature of the disc results in a removal of the plunger 30 from the bore whereby the movable contact 19 moves into physical contact with the heads 16 of the terminals 15 under the action of the spring 22.

The amount of pressure required to cause snap-action of the disc 29 is primarily a function of the disc diameter, thickness and the initial stress imparted thereto; which factors can be controlled in the manufacturing process to produce discs having a desired range of operating characteristics.

It is apparent the circular ridge on the shoulder 27 acts as a fulcrum for a lever whose length is the distance between the ridge and the point of contact between the member 32 and the disc 29. When a gradually increasing pressure is exerted circumferentially upon the disc 29 by the member 32, the disc retains its initial concave curvature until the applied pressure reaches a predetermined magnitude whereupon the disc suddenly snaps to a convex curvature. Upon gradually lowering the applied pressure the disc again snaps back to its initial concave curvature.

In a thermostatic switch adapted to control a relatively large current it is essential that the cooperating contacts open the electrical circuit quickly to extinguish the resultant electrical arc as quickly as possible. The work required to reverse the curvature of the disc 29 is the product of a relatively large force multiplied by a relatively small displacement representing the minute motion required to be imparted along the edge of the disc. On the other hand, the work performed by the disc represents a reduced force multiplied by a relatively large displacement of the plunger 30. Although the force applied to the disc may vary gradually, the action of the disc is sudden. Thus, the opening and closing of the electrical circuit, between the two terminals 15, in accordance with the action of the disc 29 will be accomplished rapidly and positively.

The operating mechanism described to this point is enclosed in the casing 11 conveniently retained in position by turning the end 33 over the base 10 and rolling the midsection at the point 34 to conform to the inturned end of the said base 10, as shown. The casing 11 is open ended to facilitate the connection of lead wires to the terminals 15.

The temperature sensitive actuating element of the thermostatic switch comprises concentrically arranged members formed of dissimilar metals, that is, metals having different thermal expansion coefficients. The difference in longitudinal expansion of the members is employed to cause actuation of the prestressed disc.

One member of the actuating element comprises the tubular shell 12 having a plug 35 and a cap 36 firmly secured to the outer end as by brazing. The shell 12 is adjustably secured to the base 10 by means of the coacting threads and the hollow nut 37 having a slightly tapered bore 65 serves to lock the two parts in predetermined, relative position. To prevent alteration of the temperature operating range to which the device has been adjusted at the factory a hole is drilled through the nut 37 and the coacting threads of the shell 12 and base 10, and a tapered pin 38 inserted therethrough. The adjustment of the device to a desired operating range will be described in more detail hereinbelow.

The tubular shell 12 is formed of a material 75 having a relatively high coefficient of thermal ex-

pansion, such as steel, and has a uniform inside diameter. However, the outside diameter of the shell varies in stages from a maximum value at the inner or threaded end to a minimum value at the outer or free end. This construction increases the speed of response of the device as a whole as the relatively thin, outer end of the shell quickly reaches the temperature of the surrounding medium.

The other member of the actuating element comprises a rod 39 disposed within the shell 12 and spaced therefrom by the spacing bushings 40. provision of an air space between the rod 39 and the tubular shell also increases the speed of response of the device as intimate contact between these parts would result in a transfer of heat from the shell to the rod thereby increasing the time required for the shell to reach the temperature of the surrounding medium. The rod 39 is made of a material having a substantially zero or negligible coefficient of thermal expansion such as, for example, Invar, a well known alloy. As shown in the drawings the rod 39 is substantially shorter than the shell 12 and a steel rod 41 is interposed between the rod 39 and the cone-shaped member 32. As the steel rod 41 and the steel shell 12 have equal expansion coefficients there will be no change in their relative lengths irrespective of the temperature of the surrounding air. Thus, the upper part of the device is insensitive to temperature changes. In other words, the temperature sensitive portion of the device comprises the free end of the shell.

In assembling the thermostatic switch the various components disposed within the base 10 are assembled as shown in the drawings after which the edge of the base 10 is turned inward over the shoulder of the subbase 14 to provide a sub-assembly or head. The relative positions of the subbase 14, washer 23 and cylinder 24 are thus fixed against further movement. The position of the ring 26 is also fixed except that the ring is subject to movement away from the base 10 when a relatively strong pressure is exerted against the shoulder 27 to overcome the pressure exerted by the relatively heavy washer 28. However, the disc 29 and the cone-shaped member 32 have freedom of axial movement within the ring 26 it being again pointed out the normal curvature of the disc is concave as shown in Figure 4.

The tubular shell 12, carrying the rods 39 and 41, is then threaded into the base 10. At this stage of the assembly the lock nut 37 is threaded well up on the thread of the shell away from the base 10. Further threading of the base 10 upon the shell 12 causes the rods 39 and 41 to abut against each other and against the plug 35 and cone 32 respectively. When this condition is reached a further threading of the base on the shell causes the cone 32 to apply a gradually increasing pressure circumferentially to the disc 29. When the pressure against the disc reaches a sufficient magnitude the disc abruptly changes its curvature from concave to convex (as shown in Figure 3) and any further increase in pressure merely results in a flexing of the spring washer 28. The sudden reversal in the curvature of the disc results in the withdrawal of the plunger 30 from the bore in the subbase 14 thereby permitting the movable contact 19 to close an electrical circuit between the terminals 15 under the action of the compression spring 22.

The amount of pressure initially applied to the disc, with proper consideration given to the dimensional factors of the co-acting parts, estab-

lishes the temperature at which the device will operate. The operating point may be checked by immersing the end of the shell 12 in a controlled temperature bath. As the temperature of the bath is increased the tubular shell 12 expands gradually in axial length. Inasmuch as the rod 39 has a negligible thermal expansion coefficient its axial length remains fixed. Consequently, axial expansion of the shell is effective to reduce the pressure exerted against the disc 29 and when the pressure is reduced to a certain magnitude the disc abruptly reverses its curvature to the normal state (concave), under which condition the plunger 30 forces the movable contact 19 out of contact with the terminals 15.

After the thermostatic switch has been adjusted to operate at a predetermined temperature the lock nut 37 is threaded upon the extension of the base 10, a hole is drilled through the nut and the tapered pin 38 forced therein.

The spring washer 28 prevents a buckling of the coacting parts when the device is subjected to low temperatures during storage, etc. At low temperatures the shell 12 contracts in length thereby increasing the pressure applied to the disc 29 beyond the original pressure applied in the original adjustment of the device as a whole. Such increase in pressure results in a flexing of the washer 28 and a corresponding movement of the ring 26. Also, the washer 28 is in the form of a closed ring with the center portion bowed or dished in. A closed spring washer so made has the unique property of exerting a maximum resistance to deformation when in the bowed state, and a decreasing resistance as the inner and outer sections approach a common, flat plane. Such a characteristic is desirable in this particular application as the washer effectively decreases the mechanical loading on the mechanism at decreasing temperature. Thus, if the parts are designed to operate properly at the normal temperature range, a decrease in temperature to as low as -50° C. will not result in a failure of the parts.

Although a thermostatic switch made as herein described is adapted to many apparent uses it is particularly well suited for the protection of electric motors having field windings insulated with a silicone compound. The silicone insulation is capable of withstanding high temperatures permitting operation of the motor at a higher temperature, in the region of 200° C., and the thermostatic control must be capable of positive operation at these temperatures. My thermostat is operatively mounted on the motor by drilling a hole in the motor end bell, inserting the device through the hole so that the end of the shell 12 lies adjacent to the motor field winding. The device is secured into position by screws or bolts passing through the apertures of the case ears 13 and into the motor end bell. The thermostat is connected into one side of the line so that current flowing through the motor passes through the terminals 15 and movable contact 19. Should the motor temperature exceed the safe limit the thermostatic switch, having been adjusted to operate at the critical value of temperature, snaps off the current by opening the electrical circuit between the two terminals 15. Any tendency of the electrical contacts to stick together cannot affect the temperature setting of the mechanism as the plunger 30 is in rapid motion when it strikes the movable contact 19. In the case of large motors the thermostatic switch contacts may control the operation of a power relay or circuit

breaker designed to control the interruption of the very high motor current.

Having now described my invention certain variations in the size, shape and arrangement of the parts will be apparent to those skilled in the art. Such variations may be made without departing from the spirit and scope of the invention as recited in the following claims.

In the claims, the application of the pressure required to cause an abrupt change in the curvature of the stressed disc is recited as being applied circumferentially to the disc. It is understood that this and similar terminology is intended to define a force which is applied substantially normal to the surface of the disc and at points forming a circle adjacent to the circumferential edge of the disc as illustrated in the structure shown in the drawings and described herein.

I claim:

1. A thermostatic switch comprising a casing open at one end and having a central aperture in the other end, a base of insulating material disposed within the open end of the casing, said base having a central bore, means securing the casing and base to prevent axial motion of one relative to the other, a pair of terminals extending through the base each terminal having a contact section extending into the bore, a cup-shaped contact in the bore of the base, a spring disposed between the base of the bore and the cup-shaped contact to bias the said contact into engagement with the contact sections of the terminals, a ring member within the casing and spaced from the base said ring member having a circumferential ridge, a snap-action disc in face contact with the ridge of the ring member, a conical ring washer disposed between the ring member and the base, a cone member having its base in circumferential contact with the disc and its apex alined with the aperture in said casing, a tubular shell having a closed outer end and an open end, a rod

within the shell and extending beyond the open end, means adjustably securing the shell to the casing whereby the rod abuts against the apex of the cone member, and a plunger having one end secured to the disc and the other end spaced from the cup-shaped contact when the curvature of the disc is convex with respect to the cone member.

2. The invention as recited in claim 1, wherein the means adjustably securing the shell to the casing comprises an axial extension of the case having an internal thread co-acting with an external thread on the shell, and a hollow nut having a tapered bore, said nut threaded on to the shell and overlapping the said extension of the case.

3. The invention as recited in claim 2 and including a transverse hole through the nut and the co-acting threads of the shell and case extending, and a tapered pin in said hole.

WILLIAM A. YONKERS.
